PATENTED MAR. 24, 1903.

I. GRIMM.

COMBINED SPLIT AND BAR CUTTING POWER SHEARS.

APPLICATION FILED DEC. 20, 1902.

NO MODEL.

UNITED STATES PATENT OFFICE.

IGNAZ GRIMM, OF CINCINNATI, OHIO.

COMBINED SPLIT AND BAR-CUTTING POWER-SHEARS.

SPECIFICATION forming part of Letters Patent No. 723,599, dated March 24, 1903.

Application filed December 20, 1902. Serial No. 135,985. (No model.)

To all whom it may concern:

Be it known that I, IGNAY GRIMM, a citizen of the United States, and a resident of the city of Cincinnati, in the county of Hamilton and State of Ohio, have invented a certain new and useful Combined Split and Bar-Cutting Power-Shears; and I do declare the following to be a clear, full, and exact description thereof, attention being called to the accompanying drawings, with the reference characters marked thereon, which form also a part of this specification.

This invention relates to improvements in the construction and arrangement of power-shears for cutting metal, more particularly iron and steel, and in shape of plates or bars, which latter, again, may be flat bars or so-called "angle-bars" or "angle-irons" or other shapes. The machines now in use for this class of work are specially constructed to suit the particular metal to be worked as to its shape and form, so that there are so-called "split-shears" to cut metal plate, "bar-shears" to cut flat bar-iron, and "angle-shears" to cut angle-bars. There are also machines which may be arranged to permit cutting of either flat or angle bars on the same machine, and there are still others which may be adjusted to permit cutting of either plate or flat bars, the capacity of these machines adapted to such alternate use being, however, generally limited as regards one of the kinds of work to be done thereon to the dimensions, particularly length, of such work, so that in all cases of such possible double use the machine as to one of the uses cannot be used as fully and advantageously as a machine constructed solely for one particular use.

The object of my invention is therefore to construct a shear adapted for use in connection with all the shapes of iron mentioned—that is, plate, flat bars, or angle-bars—the use in connection with each shape to be as convenient and as unrestricted as in a machine specially constructed for the particular kind of work.

In the following specification and particularly pointed out in the claims is found a full description of the invention, together with its operation, parts, and construction, which latter is also illustrated in the accompanying drawings, in which—

Figure 1 shows the front side of my improved power-shear, the same being arranged to cut bar-iron, particularly angle-bars, a 55 plate of metal being also shown in dotted lines as it appears during its passage through the shears while being cut. Fig. 2 is an end view of Fig. 1 with the lower part in section. Fig. 3 is a top view of the lower part of the 60 machine shown in the preceding figure—that is, it shows its bed or anvil. Fig. 4 shows a front view of my improved shear embodied in a different type of frame and used for cutting plate metal. Fig. 5 is a side view of Fig. 4; 65 and Fig. 6 shows a part of Fig. 1—that is, the operative part—and arranged for cutting flat bars.

In such machines two shear-blades or cutting-jaws are generally used, of which one is 70 held in a stationary position, while the other, usually the upper one, has a movement to and from it. The mechanical means whereby this movement is obtained forms no part of my invention.

9 is the lower jaw, seated in a socket 10, contained in the bed or anvil 11, formed by the lower part of the machine-frame and held there by bolts 12. The upper jaw (indicated by 13) has two parallel sides 13^a 13^b and is 80 supported by guiding means in a manner so that when reciprocated it moves to and from the lower jaw at an angle. These guiding means may be simply guideways, within which the side edges 13^a 13^b slide, or it may be an 85 entire inclosing casing, as shown, and being formed in part by a portion 14 of the upper part of the main frame and a removable cap 15. The lower part of this jaw 13 is shaped to form two cutting edges, one, 13^b, and another, 90 13^c, arranged substantially at right angles to each other. Of these two cutting edges the lower one, 13^b, is substantially parallel to cutting edge 9^a of the lower cutting-jaw 9, subject to such divergence as is usually provided 95 to obtain a proper self-clearing shear cut. There is, further, an upright cutting-jaw 16, fitted into a socket 17 and held therein by bolts 18. It is arranged closely to jaw 9, so that the cutting edge 16^a of it forms with cutting edge 9^a a continuous angular cutting edge, as shown in the drawings, most clearly in Fig. 1. The other or upright cutting edge 13^c on the movable jaw is arranged substan-

tially parallel to this cutting edge 16^a of the upright jaw 16, subject to such slight divergence necessary for a proper shearing cut, so that, as will be seen, four cutting edges are capable of entering simultaneously into action. Of these 13^b 13^c form a continuous angular cutting edge on the upper jaw and work in conjunction with the continuous angular edges 9^a and 16^a below. Each cutting-jaw is removably attached for grinding or renewal, the lower jaws 9 and 16 from their sockets 10 and 17 and the upper jaw 13 from within its guiding means or from a carrier 19, to which it is detachably connected. It will now be seen that with this upright jaw 16 in position angle-bars A may be cut, as shown in Fig. 1, while when it is removed the machine may be used as a so-called "split-shear" for cutting plate metal P, as shown in Figs. 4 and 5 and in dotted lines in Fig. 1. Flat bars F may be cut in either condition—that is, with jaw 16 removed or in position, as shown in Figs. 1 and 3 or 6. In the latter case this jaw may serve as a guide and stop for the flat bars while resting against it, as shown in Fig. 3, and the same as is shown in case of the angle-bar in Fig. 1.

The reciprocal motion of the upper jaw to and from the two lower ones may be obtained by any mechanical means. It may be connected to an oscillating beam 20, to which its carrier 19 is attached by a link 21 and which is actuated by a crank or eccentric 22, operated by a power-driven shaft 23, all as shown in Figs. 1 and 2, or the machine may be constructed on the customary type used in power-punches and shears and as shown in Figs. 4 and 5, the upper jaw being operated from a power-driven shaft 24 by means of an intermediate eccentric link, crank, or cam. As before stated, however, no invention is claimed for these mechanical means for operating the upper jaw. The frame should in each case be so arranged as to form no obstruction to the advancing metal when splitting plate, nor should any part of it be in the way when inserting long bars. In the frame shown in Figs. 1 and 2 this requirement is fully realized, the upper part in front being set back, as shown at 25, permitting one of the separated parts of the plate resulting from the splitting of the same to pass straight on. On the rear side the other of the split parts of the plate passes under this offset, as shown at 26 in Fig. 2, also in Fig. 4, and in dotted lines in Fig. 1. The metal readily passes under this latter offset by reason of a tendency to hang and curve downwardly, due to the action of the upper

jaw on this part of the split plate. In either case, either by formation of the frame or by attachment, a shoulder 27 should be provided on the frame for the upper end of upright jaw 16 to bear against, so as to reinforce its position against the action of the upper jaw when in angle-cutting cutting edge 13^c moves toward it. Customary adjustable gages and stops against which the ends or sides of the metal are shoved to determine the exact position of the cuts and to facilitate work when much of the same kind is to be done are implied, but not shown.

Having described my invention, I claim as new—

1. In a power-shear for splitting plate metal and for cutting bar metal, the combination of a lower cutting-jaw, an upright cutting-jaw, the cutting edges of the two being so arranged as to form a continuous angular cutting edge, the upright jaw being attached in a manner to be removable independently of the other one, an upper jaw having two cutting edges also arranged at an angle to each other and means for operating this latter jaw in a manner that its cutting edges are capable of operating simultaneously in conjunction with either or the two other cutting edges.

2. In a power-shear for splitting plate metal and for cutting bar metal, the combination of a lower cutting-jaw, having a substantially horizontal cutting edge, an upright cutting-jaw having a substantially vertical cutting edge, both these cutting edges being continuous, a socket for each of these jaws, means for securing each jaw in its socket in a manner to render each independently removable, an upper jaw having at its lower end two cutting edges 13^b 13^c arranged at an angle to each other and forming a continuous cutting edge, two parallel guiding-edges 13^a on this jaw above its cutting edge, mechanism for moving this upper jaw to and from the other jaws and supporting means engaging its guiding edges 13^a in a manner that in the movement of the upper jaw toward the lower one, the apex of the angle of the upper cutting edge is caused to move toward the apex of the reentering angle formed by the lower cutting edge.

In testimony whereof I hereunto set my signature in the presence of two witnesses.

IGNAZ GRIMM.
